UNITED STATES PATENT OFFICE.

ELZA A. NELSON, OF DEXTER, OHIO, ASSIGNOR TO THE POMEROY NOVELTY COMPANY,
OF POMEROY, OHIO, A CORPORATION OF OHIO.

BREAST-BOW FOR HARNESS.

1,110,338.

Specification of Letters Patent. Patented Sept. 15, 1914.

Application filed December 7, 1911. Serial No. 664,364.

To all whom it may concern:

Be it known that I, ELZA A. NELSON, a citizen of the United States, residing at Dexter, in the county of Meigs and State of 5 Ohio, have invented a certain new and useful Improvement in Breast-Bows for Harness, of which the following is a specification.

This invention relates to breast bows or devices for protecting the throat and breathing passages of a horse while drawing heavy 10 loads and its object is to simplify and cheapen the construction of such devices and render their manipulation easy and expeditious.

15 The invention is embodied in the example shown in the accompanying drawings, set forth in the following description and pointed out in the claim appended hereto.

In the said drawings—Figure 1 is a top 20 plan view of the bow showing it attached to traces. Fig. 2 is a front elevation of the same. Fig. 3 is a horizontal section on the line $y-y$ Fig. 2. Fig. 4 is a cross section on the line $x-x$ Fig. 3 looking toward the 25 right.

In the views 5 designates the outer member of the breast bow and 6 the inner member. The outer member 5 is a longitudinally curved structure of sheet metal bent to U-form having one flat or shank end 5^a for riveting the member to a trace 7. The inner bow member 6 is also a longitudinally curved structure of sheet metal bent to U-form and having one flat or shank end 6^a for riveting 30 that member to a trace 7^a. The inner bow member 6 is curved to correspond to the interior of the outer member and it is made of dimensions to fit snugly within said outer member 5. The said outer member 5 near its 35 shank end is provided with a bridging transverse pin 5^b fixed therein. The two walls of the free end of the inner bow member 6 are similarly cut to provide a double hook, as seen at 6^b that can catch behind the transverse pin and prevent separation longitudi- 40 45

nally of the two members when they are closed together. The end of the double hook is preferably rounded on an arc having the axis of the pin 5^b as its center so that the two parts of the bow must be swung to a 50 wide angle (see broken lines Fig. 3) with reference to each other and with the pin as the axis to permit the bow members to be separated from each other. The bows are held together and from flexion when on the 55 horse by the proximity of the ends 5^a and 6^a to the horse's breast. The pin 5^b acts as a latch to prevent lengthwise separation of the bows. Said pin 5^b also acts as a fulcrum on which one or both parts 5 and 6 are 60 turned by hand in effecting the separation. When so constructed such a separation cannot take place when the device is upon a horse except by positive manipulation for 65 the purpose but because of the simplicity of the construction this separation can be effected in a moment and with the greatest ease.

When formed as herein shown and described the parts can be manufactured with 70 dies rapidly and in great quantities.

What I claim is:

A breast bow for harness comprising, in combination, two pieces of sheet metal curved longitudinally and of U-form in cross 75 section to fit one within the other and around the breast of a horse, said pieces being open at the sides adjacent the horse's breast, the outer of said pieces having a transverse pin and the inner piece having a 80 hook cut in its wall to engage said pin, said pieces also having shank extensions 5^a and 6^a which lie and move in a plane substantially coinciding with the plane in which the said 85 longitudinally curved pieces lie and move.

ELZA A. NELSON.
